US00D674750S

(12) **United States Design Patent**
Ito

(10) **Patent No.:** **US D674,750 S**
(45) **Date of Patent:** **** Jan. 22, 2013**

(54) **RECHARGEABLE BATTERY**

(75) Inventor: **Syun Ito**, Kyoto (JP)

(73) Assignee: **GS Yuasa International Ltd.**,
Kyoto-Shi, Kyoto (JP)

(**) Term: **14 Years**

(21) Appl. No.: **29/393,868**

(22) Filed: **Jun. 10, 2011**

(30) **Foreign Application Priority Data**

Dec. 10, 2010 (JP) 2010-029518

(51) **LOC (9) Cl.** **13-02**

(52) **U.S. Cl.** **D13/120**

(58) **Field of Classification Search** D13/102–106,
D13/110, 118–121, 133, 154, 184, 199; 429/96–100,
429/128–131, 149, 163–170, 176, 178

See application file for complete search history.

(57) **CLAIM**

The ornamental design for a rechargeable battery, as shown and described.

DESCRIPTION

FIG. 1 is a perspective view of a rechargeable battery showing my new design;

FIG. 2 is a front elevational view thereof;

FIG. 3 is a rear elevational view thereof;

FIG. 4 is a left, side view thereof;

FIG. 5 is a right side view thereof;

FIG. 6 is a top plan view thereof; and,

FIG. 7 is a bottom plan view thereof.

The broken lines depict environmental subject matter only and form no part of the claimed design.
